EXHIBITING ATTACHMENT FOR PROJECTING MACHINES

Irving L. Cook, Gillett, Wis.

Application June 9, 1936, Serial No. 84,352

8 Claims. (Cl. 88—27)

This invention relates to exhibiting attachments for projecting machines and has for an object to provide an interchangeable photographic film holder for developing, drying and projecting machines, the film holder having a central mounting opening for assembling the holder with the selected machine, the film holder having an annular series of radially disposed openings to receive the photographic films, especially dentists, 5 X-ray films, and permit either the developing materials being brought into contact with the films, or to permit air currents to dry the films by spinning the disk on a revolving shaft, or to permit light being projected through the films when 10 the disk is applied to a projecting machine.

A further object of the invention is to provide a novel mechanism for adjustably mounting the film holder on a projecting machine in such manner that regardless of what position the 20 images on the films may extend, that is, upside down, or otherwise, the holder may be adjusted quickly and easily to cause the image to be projected correctly.

A further object of the invention is to provide 25 a device of this character which will be formed of a few strong simple and durable parts, which will be inexpensive to manufacture, and which will not easily get out of order.

With the above and other objects in view the 30 invention consists of certain novel details of construction and combinations of parts hereinafter fully described and claimed, it being understood that various modifications may be resorted to within the scope of the appended claims without departing from the spirit or sacrificing any of the 35 advantages of the invention.

In the accompanying drawings forming part of this specification,

Figure 1 is a side elevation of apparatus constructed in accordance with the invention and embodying a projecting machine, a photographic film holder adjustably mounted to rotate on its own axis or to rotate in an orbit around the axis of light projection of the projecting machine, whereby inverted images may be projected right side up.

Figure 2 is a front elevation of the support for 50 adjustably mounting the film holder on the barrel of the projecting machine, and showing diagrammatically in dotted lines adjusted positions of the film holder.

Figure 3 is an enlarged longitudinal sectional view taken on the line 3—3 of Figure 2.

Figure 4 is a front elevation of the swivel ring 55 member of the support.

Figure 5 is a front elevation of the screen and showing the member for mounting the same on the lamp housing of the projecting machine.

Figure 6 is a detail longitudinal sectional view taken on the line 6—6 of Figure 5. 5

Figure 7 is a front elevation of the reflector and the bracket for adjustably mounting the same on the base of the projecting machine.

Figure 8 is a detail longitudinal sectional view taken on the line 8—8 of Figure 7. 10

Figure 9 is a front elevation of the photographic film holder and showing a film in one of the openings thereof.

Figure 10 is a detail sectional view taken on the line 10—10 of Figure 9. 15

Figure 11 is an enlarged transverse sectional view taken on the line 11—11 of Figure 10.

Referring now to the drawings in which like characters of reference designate similar parts in the various views, 12 designates a film holder comprising a disc of thin sheet metal provided centrally with an opening 13 for mounting the disc as will be presently described. The disc is provided with radially disposed struck up angular clips 14 and with an annular series of struck up clips 15. The radially disposed clips and annular clips are arranged in groups of four, each group confining a film 16 to the disc, the films, for example, being dentists' X-ray films, and extending radially upon the disc, as shown in Figure 9. An annular series of substantially rectangular openings 17 are formed in the disc, each opening being within the space bounded by a group of four clips 14—15 so that both sides of the central portion 18 of film 16 are exposed for treatment such as developing, drying, or projecting. 30

The film holder is provided with an annular series of indentations 19 concentric with the central opening 13, each pair of diametrically opposed indentations being located in a diameter of the disc passing through the median longitudinal lines of a pair of oppositely disposed films. The purpose of these openings is to center the film accurately with respect to the axis of light projection of a projecting machine such as is shown in Figure 1. 40

The projecting machine is of the conventional type including a light housing 20 mounted on a base 21, there being a standard 22 on the base in front of the light housing for supporting the lens barrel 23 of the projecting machine. 50

For mounting the above described film holder on the projecting machine, a stationary channeled ring 24 is disposed concentrically on the 55

end of the beam concentrating shield 25 of the projecting machine and is supported by diverging legs 26 each comprising a tube 27 which is fixed at one end to the rear face of the ring, 5 and a rod 28 which is telescopically received in the tube and held in adjusted positions therein by a set screw 29. Each rod is directed outwardly at the bottom to provide a foot 30 which is fixed to the projecting machine base 21 by a screw 31. The stationary ring is provided in the base of the channel thereof with indentations 32 disposed 90 degrees apart, the purpose of which will presently appear.

A movable ring 33 is rotatably mounted in the 15 channel of the stationary ring 24, and is preferably a resilient split ring having ears 34 which are adjustable toward or away from each other by a screw pin 35 carried by one of the ears and a nut 36 on the pin bearing against the other 20 ear. Movement of the nut varies the diameter of the ring and increases or diminishes the frictional engagement of the ring with the stationary ring. The ring is provided with a rod 37 which extends radially from one side of the ring and 25 receives a block 38 for supporting the film holder 12 on the rod.

The block 38 is provided with a set screw 39 which holds the block in adjusted positions longitudinally of the rod and permits of assembly and 30 disassembly of the block on the rod. The end of the rod is provided with a stop 40 which may be simply a pin assembled with the rod and having a head of larger diameter than the rod. Removal of the stop permits removal of the block 38 and 35 when the stop is in place, should the set screw 39 be loosened, the stop will prevent the block from escape from the rod 37.

For mounting the film holder 12 on the block a 40 threaded pin 41 is screwed into the front face of the block and receives a nut 42 having a tubular flange 43 which enters a cylindrical cap 44. A 45 helical spring 45 is housed in the cap between the end wall of the cap and the end of the tubular flange on the nut. The film holder is mounted for rotation on the pin 41 as an axis by removing the nut 42 and cap 45 then the pin 41 may be slipped through the central opening 13 in the disc and the cap and nut replaced. The nut 42 50 may now be tightened to compress the spring 45 thereby urging the cap 44 to frictionally engage the disc and act as a brake.

A pair of ball stops 46 are disposed in seats 47 formed in the front face of the block 38 and are yieldably urged outwardly by helical springs 55 48 disposed in openings 49 formed in the block on opposite sides of the pin 41. These ball stops 46 enter a pair of the indentations 19 in the rear face of the disc 12 and center a film 16 with respect to the axis of light projection indicated 60 at 50 in Figure 1.

Referring now to Figure 3 it will be seen that a ball stop 51 is disposed in a seat 52 formed in the inner periphery of the movable ring 33. The ball stop is urged toward the center of the 65 ring by a helical spring 53 disposed in an opening 54 formed in the ring and in the rod 37. This ball stop rides into the indentations 32 disposed 90 degrees apart in the channel of the stationary ring 24 and locates the rod 37 at any selected 70 indentation for correctly projecting an image regardless of whether it be located upside down or otherwise on the film.

The projected image is reflected from an inclined mirror 55 onto a screen 56 and there displayed greatly magnified so that in the case of 75

the image of a tooth, for example, defects will be readily apparent to the observer.

The mirror is provided with an attaching arm 57 which terminates in a ball 58 that is frictionally engaged, as shown in Figure 8, between a plug 59 in a casing 60 and a disc 61 which is slidably fitted in the casing and is urged against the ball by a helical spring 62. Thus the mirror may be adjusted to various angular positions to properly locate the reflected image on the screen. 10 The casing is provided with a stem 63 which is adjustably mounted for vertical movement in a tubular bracket 64 and held in adjusted positions therein by a set screw 65. The stem is provided with a horizontal leg 66 which is secured 15 by straps 67 and set screws 68 to the base 21 of the projecting machine below the lens barrel 23.

The screen 56 is preferably formed of sheet metal and is provided at the top with a trough 69 to receive a roll 70 of paper which may be 20 drawn down over the front face of the screen as shown at 71 and there secured by clips 72 placed astride the edges of the sheet and the screen, or the sheet may be otherwise fastened in place as desired. The screen is provided at 25 the bottom with a bracket arm 73 which terminates in a ball 74 that is confined in a seat 75 formed in a post 76 by means of a screw cap 77 so that the angular inclination of the screen may be adjusted as desired. The post terminates in 30 a flange base 78 which is supported upon the top of the light housing 20, as shown in Figures 1 and 5.

A pair of screw pins 79 are threaded into the 35 post 76 and receive hooks 80 which are engaged underneath the ventilator 81 of the light housing. Nuts 82 are threaded on the pins and force spacing tubes 83 against the hooks and cause the same to tightly grip the ventilator to mount the 40 screen on the projecting machine. Loosening of the nuts permits the hooks to be slackened off to facilitate removal of the screen.

In operation the film holder has three separate 45 uses, in sequence, for the developing, drying and projecting of films. After the exposures are made, the films 16 are applied to the clips of the holder, as shown in Figure 9, and no particular care need be taken as to whether the images are right-side up or not. The film holder with the films thereon is now revolved in a developing tank of conventional type, the central opening 13 forming means rotatably mounting the holder on the usual shaft in the developing tank. After the developing operation the film 50 holder with the developed films thereon is placed on a suitable driven shaft and rapidly rotated for a period of about three minutes to thoroughly dry the films. The film holder with the dried 55 films thereon is now placed on the pin 41 and the block 38 is adjusted so that the center of any selected film will coincide with the axis of light projection of the projecting machine. If it is found that the image is inverted, or otherwise not in natural position, when reflected upon the 60 screen, it is simply necessary to swing the rod 37 to the right or to the left in an orbit around the axis of light projection as shown diagrammatically by dotted lines in Figure 2 to so reverse the film that the image will appear right-side up when reflected upon the screen.

From the above description it is thought that the construction and operation of the invention will be fully understood without further explanation.

What is claimed is:

1. Exhibiting means for a projecting machine having a light projecting means and a focusing lens forwardly thereof, said exhibiting means including relatively movable nested rings adapted to be disposed in rear of the focusing lens of a projecting machine, concentric with the axis of light projection, an arm projecting radially from one of the rings, a horizontal axis on said arm, a holder having a circular series of film holders mounted to rotate thereon, means for adjusting the rings to dispose the arm at selected radial positions with respect to the axis of light projection, and means for centering a selected film holder in the axis of light projection.
- 5 2. Exhibiting means for a projecting machine having a light projecting means and a focusing lens forwardly thereof, said exhibiting means including the combination of a stationary ring adapted to be disposed in rear of the focusing lens of a projecting machine concentric with the axis of light projection, a ring rotatably mounted on the stationary ring, an arm projecting radially from the rotary ring and movable with said rotatable ring in an orbit around the stationary ring, a horizontal axis on said arm, a holder having a circular series of film holders mounted to rotate thereon, means between said rings for disposing the rotatable ring with the arm at selected adjusted positions around the stationary ring, and means between the holder and the arm for centering a selected film holder in the axis of light projection.
- 10 3. Exhibiting means for a projecting machine having a light projecting means and a focusing lens forwardly thereof, said exhibiting means including the combination of a stationary ring adapted to be disposed in rear of the focusing lens of a projecting machine concentric with the axis of light projection, a ring rotatably mounted on the stationary ring, an arm projecting radially from the rotary ring and movable in an orbit around the stationary ring by movement of the rotary ring, a block adjustably mounted on the arm, an apertured film supporting disc having a central opening, means on the block engageable through the central opening for mounting the disc to rotate on a horizontal axis, means on the disc for securing photographic films over the apertures on the disc in a circular series concentric with said central opening, a circular series of sockets on the disc concentric with said central opening, a spring pressed stop on the block selectively engageable in said sockets for centering a selected film in the axis of light projection, and means between both rings for disposing the arm at selected adjusted positions around the stationary ring.
- 15 4. Exhibiting means for a projecting machine having a light projecting means and a focusing lens forwardly thereof, said exhibiting means including the combination of a stationary ring adapted to be disposed in rear of the focusing lens of a projecting machine concentric with the axis of light projection, a ring rotatably mounted on the stationary ring, an arm projecting radially from the rotary ring and movable in an orbit around the stationary ring by movement of the rotary ring, there being a plurality of sockets on the stationary ring, a spring pressed stop on the rotary ring at the base of said arm selectively engageable in said sockets to hold the arm stationary at various adjusted positions radially with respect to the axis of light projection, a film holder mounted to rotate on a horizontal axis
- 20 5. Exhibiting means for a projecting machine having a light projecting means and a focusing lens forwardly thereof, said exhibiting means including an adjustable supporting means comprising an adjustable axis for a film holding disc, a film holding disc having a circular series of film holders to be rotatably mounted on said adjustable axis, means for holding the film holder disc for centering each of the film holders with respect to the light projecting means and focusing lens, a movable nested ring support for said adjustable axis of the film holding disc, and a stationary co-acting ring support for said movable nested ring support whereby any film in any of the film holders may be axially rotated with respect to the light projecting means and focusing lens.
- 25 6. Exhibiting means for a projecting machine having a light projecting means and a focusing lens forwardly thereof, said exhibiting means including an adjustable supporting means comprising an adjustable axis for a film holding disc, a film holding disc having a circular series of film holders to be rotatably mounted on said adjustable axis, means for holding the film holder disc for centering each of the film holders with respect to the light projecting means and focusing lens, a movable nested ring support for said adjustable axis of the film holding disc, a stationary co-acting ring support for said movable nested ring support, and clamping means on said movable ring to secure the same to said stationary ring, whereby any film in the film holder may be held in any desired axially rotated position with respect to the light projecting means and focusing lens.
- 30 7. Exhibiting means for a projecting machine having a light projecting means and a focusing lens forwardly thereof, said exhibiting means including an adjustable supporting means comprising an adjustable axis for a film holding disc, a film holding disc having a circular series of film holders to be rotatably mounted on said adjustable axis, means for holding the film holder disc for centering each of the film holders with respect to the light projecting means and focusing lens, a movable nested ring support for said adjustable axis of the film holding disc, a stationary co-acting ring support for said movable nested ring support, clamping means on said movable ring to secure the same to said stationary ring, whereby any film in the film holder may be held in any desired axially rotated position with respect to the light projecting means and focusing lens.
- 35 8. Exhibiting means for a picture projection machine having a space for receiving films to be projected, said exhibiting means including a rotatable holder having a circular series of film holders, means for mounting said film holder for rotation for positioning the film holders successively in the film space of the projecting machine, and means for rotating said mounting for the film holder about the center of the film projecting space of the projecting machine.
- 40 45 50 55 60 65 70 75
